UNITED STATES PATENT OFFICE.

ETTA L. JENKINS, OF NEW YORK, N. Y., ASSIGNOR TO THE BUTTERICK PUBLISHING COMPANY, (LIMITED,) OF SAME PLACE.

DESIGN FOR A GIRL'S DRESS.

SPECIFICATION forming part of Design No. 17,942, dated December 13, 1887.

Application filed November 10, 1887. Serial No. 234,872. Term of patent 3½ years.

To all whom it may concern:

Be it known that I, ETTA L. JENKINS, of the city, county, and State of New York, have invented and produced a new and original 5 Design for a Pattern of a Girl's Dress; and I do hereby declare that the engraved prints accompanying this specification convey to any one accustomed to using paper patterns a clear understanding of how a garment made 10 up by the pattern will appear.

The design shows a long round waist that exhibits a closing at the back and a full plastron on the front, the plastron tapering toward the bottom and displaying honeycombing in 15 a pointed outline at the top; a full skirt that exhibits honeycombing in a series of points all round the top; full sleeves that display gathers at the top, cuffs at the bottom, and honeycombing at the back above the cuffs, and a 20 standing collar.

What I claim as my invention, and desire to secure by Letters Patent, is—

The design for a girl's dress, as shown in the engraved prints accompanying this specification.
